G. D. FISH.
DENTAL SURVEYING APPARATUS,
APPLICATION FILED OCT. 6, 1917.
1,296,643.

Patented Mar. 11, 1919.

UNITED STATES PATENT OFFICE.

GILBERT DUDLEY FISH, OF NEW YORK, N. Y., ASSIGNOR TO FREDERICK L. STANTON, OF NEW YORK, N. Y.

DENTAL SURVEYING APPARATUS.

1,296,643.

Specification of Letters Patent. Patented Mar. 11, 1919.

Application filed October 6, 1917. Serial No. 195,018.

To all whom it may concern:

Be it known that I, GILBERT DUDLEY FISH, a citizen of the United States, and a resident of the city, county, and State of New York, (whose post-office address is 28 West 39th street, New York city,) have invented a new and useful Improvement in Dental Surveying Apparatus, of which the following is a specification.

The object of my invention is to provide a dental surveying apparatus of the class shown in the Hanau Patent, No. 1,230,156, patented June 19th, 1917, and to simplify and improve such apparatus and make it so that it may be applied directly to a pantograph so that a survey may be made on the same scale as the article surveyed or on a larger or a smaller scale as may be desirable. These and other objects are accomplished by my invention, one embodiment of which is hereinafter more particularly set forth.

For a more particular description of my invention reference is to be had to the accompanying drawings forming a part hereof, in which the figure shows a side elevation of my improved apparatus as applied to one arm of a pantograph.

The arm 1, of a pantograph of the conventional kind, is mounted on a suitable table 2 which has an opening 3, below which is a bracket 4, which is preferably secured to the table, and from the lower portion of this bracket 4 rise leveling screws 5 which are pointed at their upper ends and carry a suitable object support 6. This object support is provided with two or more clamps 7 which are preferably adjustably mounted thereon and at their upper ends these clamps are provided with adjusting screws 8 by means of which the object to be surveyed, as a casting of a set of teeth 9, may be accurately placed and securely held below the opening 3 in the table 2. The object to be surveyed is placed below the level of the table so as to be out of the way at all times and accessible to an attachment placed on an ordinary pantograph.

The arm 1 has a number of slides 10, 11 and 12 mounted thereon, which slides may be held by their respective set screws 13, 14 and 15, in any desired position in a manner that will now be described, for a purpose that will be specified.

The slide 10 carries a curved arm 16 which

is screw threaded at its free and upper end to receive a corresponding micrometer screw 17 and it is also provided with a scale 18 which runs downwardly and parallel with the axis of the screw 17. The scale 18 is divided in any desired way, as in millimeters, and the pitch of the threads on the micrometer 17 is made to correspond. The upper end of the screw 17 is provided with a knurled head 19 and near the lower end is placed a collar 20 which may have suitable markings on its upper surface. In the preferred embodiment of my invention the markings are such that when the micrometer is used, readings may be had down to a thousandth of a centimeter as this is found sufficient for all practical purposes. The lower end of the micrometer screw 17 is pointed and takes into a corresponding opening in a spindle 21 which slides freely in a guide 23 that is preferably made integral with the slide 12. The spindle 21 is provided with an adjustable collar 24 which surmounts a coil spring 25 substantially as shown in the preferred embodiment of my invention, and this spring 25 normally keeps the spindle 21 up against the point of the micrometer screw 17. It is obvious, from the foregoing, that the spindle 21 may be lowered at any time or raised, as the case may be, by turning the head 19 of the screw 17. The lower end of the spindle 21 is provided with a collar 25 against which is placed a pointer 26 with its point 27 exactly in the axis of the spindle 21, as nearly as possible. The pointer 26 is mounted on a washer 28 which in turn is mounted on a coil spring 29 and this is held by a cap screw 30 mounted at the lower end of the spindle 21 so that the pointer 26 may be swung into one position or another, during the use of the apparatus, as may be convenient, without changing the position of the point 27 relatively to axis of the spindle 21.

The slide 12 has an upwardly extending arm 31 in which is mounted a screw 32, and this screw carries a nut 33 which is placed accurately between gears 34 which rise from the slide 11. The purpose of this nut 33 and the parts connected therewith is to enable one to accurately adjust the slide 12 from the slide 11 by first loosening the screws 13 and 15 and tightening the screw 14, and then both the slides 10 and 12 may be adjusted accurately from the slide 11 as a base of 116

operations. When in place they may be fixed in place by their respective screws.

In view of the foregoing, the operation of my improved apparatus will be readily understood. Assuming a casting 9 of teeth is in position as shown and the apparatus has been properly adjusted and the screws 15, 14 and 13 made tight so as to hold the parts which are carried by the arm 1, this 10 arm is swung into the desired position above the particular part of the casting which is to be surveyed and then the head 19 is turned until the point 27 is at the right position and then a mark may be made by the pantograph 15 and in case the elevation of the position of this point is to be determined and recorded, it may be by reading the marks on the collar 20 and on the scale 18 and recording what is read. The point 27 is then shifted by moving the spindle 21 and the screw 19, as above 20 described to the next desired position, and then the record is made on a piece of paper and recorded as before. These operations are repeated until all the desired points are 25 accurately located and recorded.

While I have shown and described one embodiment of my invention, it is obvious that it is not restricted thereto, but is broad enough to cover all structures that come 30 within the scope of the annexed claims.

Having thus described my invention, what I claim is:

1. In a device of the class described, a 35 pantograph arm adapted to carry a pointer, adjustable means on that arm for locating

the pointer in a direction lateral to the arm and means for indicating the amount the pointer is lowered or raised.

2. In a device of the class described, a pantograph arm, a table with an opening 40 therein, means below said opening for holding an article to be surveyed, a spindle and means for mounting the same from said arm so that it may be used to determine the exact location of a point in more than one plane. 45

3. In a device of the class described, a pantograph arm, a table with an opening 50 therein, an object support adapted to hold an object below said opening, a spindle adapted to move vertically, a mounting for said spindle connected to said arm, and a micrometer means for raising and lowering said spindle.

4. In a device of the class described, a pantograph arm, a spindle adapted to move laterally on said arm, means for connecting 55 said spindle and said arm so that the spindle may move laterally, micrometer means for moving said spindle laterally, and a pivoted point on said spindle with the point substantially in the axis of the spindle at all times. 60

5. In a device of the class described, a pantograph arm, a series of slides mounted on said arm, a micrometer screw connected to one of said slides, a vertically movable spindle connected to another of said slides 65 and an adjusting mechanism connected to the third of said slides.

Signed at the city, county and State of New York, this 31st day of August, 1917.

GILBERT DUDLEY FISH.
